UNITED STATES PATENT OFFICE.

LEONARD O. FAIRBANKS, OF NASHUA, NEW HAMPSHIRE.

BEVEL ATTACHMENT FOR BENCH-PLANES.

Specification of Letters Patent No. 31,707, dated March 19, 1861.

To all whom it may concern:

Be it known that I, LEONARD O. FAIRBANKS, of the city of Nashua, county of Hillsboro, and State of New Hampshire, have invented a new and useful Square and Bevel Attachment for Planes or other Bench-Tools; and I do declare the following is a full and exact description thereof, reference being had to the annexed drawings.

10 The object of my invention is to enable persons using the ordinary bench planes to produce a square or any required bevel with certainty and despatch, without the extraneous aid of square and bevels.

15 The nature of my invention consists in attaching to bench planes a clamp with an adjustable guide, and is constructed as follows: I construct a clamp A, Figure 1, of such size as will readily receive between its 20 lugs B and binding screw C the different sizes of planes, in such a manner that will secure the plane of the lugs in the square of

the plane, as shown in perspective (Fig. 2). To the lugs is connected a guide plate D whose proportion is such as to secure the 25 steadiness of a guide. At the foot of the upright A and at right angles with the face of the guide D is an adjusting screw H which is operated by a stationary nut F. When the clamp is attached to the plane the 30 guide plate is adjusted either at right angles with the plane stock, for the purpose of obtaining a square edge, or set at any required angle, for a bevel, by means of the adjusting nut F.

What I claim as my invention and for which I desire to secure Letters Patent is—

The attaching of an adjustable guide to the stocks of bench planes, substantially in the manner and for the purpose set forth.

LEONARD O. FAIRBANKS.
